CLAIM

The ornamental design for a glare shield with strap for an electronic device, as shown and described.

DESCRIPTION

FIG. 1 is an exploded front left side perspective view of a glare shield with strap for an electronic device showing my new design;

FIG. 2 is a front left side perspective view thereof, with the strap wrapped around the glare shield;

FIG. 3 is an exploded front right side perspective view thereof;

FIG. 4 is a front right side perspective view thereof, with the strap wrapped around the glare shield;

FIG. 5 is an exploded front elevational view of FIG. 1;

FIG. 6 is a front elevational view of FIG. 2;

FIG. 7 is an exploded rear elevational view of FIG. 1;

FIG. 8 is a rear elevational view of FIG. 2;

FIG. 9 is an exploded left side elevational view of FIG. 1;

FIG. 10 is a left side elevational view of FIG. 2;

FIG. 11 is an exploded right side elevational view of FIG. 1;

FIG. 12 is a right side elevational view of FIG. 2;

FIG. 13 is an exploded plan view of FIG. 1; and,

FIG. 14 is a bottom plan view of FIG. 2.

The broken lines environmental showing of an electronic device is for illustrative purpose only, and forms no part of the claimed design.

The characteristic feature of the design resides in the glare shield being wrapped around the bottom and both sides with the strap.
